ATTORNEY.

UNITED STATES PATENT OFFICE

2,024,692

TOOTHBRUSH HOLDER

Richard Kirmss, Brooklyn, N. Y.

Application July 7, 1933, Serial No. 679,279

2 Claims. (Cl. 206—15.1)

The present invention relates to an improvement in tooth brush receptacles and has for its object an improvement in the means for attachment and detachment of the receptacle from a wall affixed base, so that the receptacle may be removed and deposited in a bag or suit case when the user is traveling and may be readily and quickly replaced on its wall support.

Another feature is an improved means for delivering the tooth brush from the holder when desired with an easily, manually operated means.

These and other features will be apprehended as the herein description proceeds, and it is obvious that changes may be made in the structure herein without departing from the spirit hereof or the scope of the claims herein.

In the drawing,

Fig. 1 is a front elevation of the receptacle, mounted on its wall affixed base;

Fig. 2 is a side elevation of the receptacle partly broken away and removed from its wall base;

Fig. 3 is a side view of the wall base;

Fig. 4 is a fragmentary view of the rear of the receptacle;

Fig. 5 is a vertical sectional view of the receptacle, taken on the line 5—5, Fig. 1 looking in the direction of the arrow; and

Fig. 6 is a perspective view of the brush lifter slide, removed from receptacle.

The receptacle comprises a rectangular housing 1, having four walls and is made of any suitable sheet material such as metal, or celluloid, said housing being elongated in its vertical dimensions, when used as a wall supported means, to

house a single tooth brush B, shown dotted in Fig. 5. It has an open bottom 7, two side walls 5 and 6, a front wall 3 and a rear wall 4, and its upper open end is closed by a snap cover 13, pivoted by ears 10—10 to the upper of the housing

40 on a pivot pin 11, which is held by extensions 8—8 of the housing, Fig. 4. A tension spring 12 coiled about the shaft 11 and having one of its ends pressing upon the lid 13, keeps the said lid in normally closed position, as in Fig. 5.

45 Internally mounted within the receptacle is a slideable brush lifter comprised of a single strip of material bent to form a vertical wall 19, and a right angled offset platform 20, and as in Fig. 6, the wall 19 is provided with a threaded stud 18, which is riveted to said wall, as at 21.

The front wall 3 is provided with an elongated slot 17, through which the threaded stud 18 protrudes when the brush lifter is in its normal non-operative position as in Fig. 5. It will thus be seen that the platform 20, forms a movable bottom

closure for the open bottom end of the receptacle.

A threaded finger nut 22 is then screwed tightly on the stud 18, and affords means, for lifting the brush B upwardly, as shown dotted at A, Fig. 5, such lifting action, causing the brush B to 5 push up the snap cover 13, as shown dotted and exposing enough of the brush end to enable the user to remove the brush for use. To replace the brush, the snap lid is raised, the brush is dropped into the receptacle and the lid automatically closes 10 when the lifter 19—20 regains its normal lower brush holding position. The two terminals of the slot 17, act as stops to limit the movement of the brush lifter in either direction.

The wall base member 2 as shown in Figs. 1 15 and 3, comprises a strip of suitable material is bored at or near its both ends to receive wall fastening screws, which have a shouldered portion 16, directly under the slotted heads 15, so that when the base plate 2 is affixed to a wall by 20 the screws, a space is left between the front face of plate 2 and the screw head 15.

The rear wall 4 of the receptacle is provided with a pair of keyhole or bayonet slots 14—14, Figs. 4 and 5, which register with the screw heads 25 15—15, so that, by entering the screw heads into the large portion of the holes 14—14, and then pushing the receptacle downward, the underside of the heads 15 are engaged with the inside face 30 of the rear wall 4, and upon the screw shoulders 16—16, and the receptacle is thus removably attached to the base plate 2.

As thus described the receptacle is removably affixed to its wall base plate. If the user desires 35 to take the receptacle and brush, during travel, the receptacle is lifted upwardly and is thereby detached from the plate 2 and may then be packed with the travel luggage.

I claim as my invention:

40 1. A tooth brush receptacle, including in combination, a tooth brush completely enclosed therein, and comprising a vertically wall mounted casing open at both ends, a spring closed, vertically operating cover closing one end, a vertically moving 45 able interiorly located slide wall adjacent the inner face of one wall of the casing and having a brush supporting platform thereon, said platform forming a movable bottom for one end of said casing, said wall being provided with a vertical 50 slot therein and a single stud located external to said wall and connected to said slide wall through said slot, for manual, vertical reciprocation of said platform, to cause the enclosed brush to open said cover when the slide wall is lifted. 55

2. A tooth brush receptacle, including, in combination, a tooth brush completely enclosed therein, and comprising a vertically wall mounted casing open at both ends, a vertically operating, spring closed, hinged cover at the upper end of said casing, a vertically movable, interiorly mounted slide wall adjacent the inner face of one wall of the casing and having a brush supporting platform thereon, said platform forming a movable closure for the bottom open end of said

casing, said wall having an elongate vertical slot therein and a single stud located externally of said wall and being connected through said slot to said slide wall for manual vertical reciprocation of said platform, to cause the enclosed brush to open said cover when the slide wall and platform are lifted, adjacent walls of the casing acting as guides for said movable slide wall and platform. 5
